US0D1047708S

(12) **United States Design Patent** (10) **Patent No.:** **US D1,047,708 S**
(45) **Date of Patent:** **** Oct. 22, 2024**

(54) **DETECTION APPARATUS**

(71) Applicant: **Bureau d'Electronique Appliquée en abrégé B.E.A., société anonyme, Angleur (BE)**

(72) Inventors: **Kevin Gillissen**, Tongeren (BE); **Paul Haberl**, Munich (DE); **Stefan Eckstein**, Munich (DE)

(**) Term: **15 Years**

(21) Appl. No.: **35/516,132**

(22) Filed: **Sep. 30, 2022**

(80) **Hague Agreement Data**

Int. Filing Date: **Sep. 30, 2022**

Int. Reg. No.: **DM/226094**

Int. Reg. Date: **Sep. 30, 2022**

Int. Reg. Pub. Date: **Jan. 27, 2023**

(57) **CLAIM**

The ornamental design for a detection apparatus as shown and described.

DESCRIPTION

1. Detection apparatus

1.1 : Perspective

1.2 : Back

1.3 : Front

1.4 : Right

1.5 : Left

1.6 : Top

1.7 : Bottom

Designation of the design: new detection device head. Use of the design: it is used as a head of a detection device. Characteristics of the design: the shape in its entirety. Designs that best illustrate the features of the design: reproduction 1.1 (perspective view) and reproduction 1.6 (top view).

The broken lines shown are included for the purpose of illustrating portions of the detection apparatus that form no part of the claim.

1 Claim, 7 Drawing Sheets
